UNITED STATES PATENT OFFICE.

LUCIUS N. WADE, OF MAY VIEW, WASHINGTON.

BARN-YARD CART.

1,122,756.

Specification of Letters Patent.

Patented Dec. 29, 1914.

Application filed May 2, 1914. Serial No. 836,020.

To all whom it may concern:

Be it known that I, LUCIUS N. WADE, a citizen of the United States, residing at May View, in the county of Garfield and State of Washington, have invented certain new and useful Improvements in Barn-Yard Carts, of which the following is a specification, reference being had to the accompanying drawings.

10 This invention relates to a barn yard cart. The object of the invention is to provide a structure of this character which may be readily drawn over the ground by hand to all parts of the barn yard or barn, and into 15 which manure or other like matter may readily be deposited and held while being transferred to a place of deposit.

With the above and other objects in view, as will appear as the nature of the invention 20 is better understood, the same consists in the novel construction and arrangement of parts of a barn yard cart, as will be hereinafter fully described and claimed.

In the accompanying drawings forming 25 a part of this specification, and in which like characters of reference designate corresponding parts: Figure 1 is a view in side elevation of a barn yard cart embodying the features of the invention; Fig. 2 is a 30 front elevation thereof; Fig. 3 is a side elevation of a slightly modified form; Fig. 4 is a similar view of another modified form; Fig. 5 is a view in rear elevation, on an enlarged scale, of the door releasing mechanism; Fig. 6 is a view taken on line 6—6 35 of Fig. 5; and Fig. 7 is a view, in side elevation, on an enlarged scale, of a part of the structure.

Referring to the drawings, 1 designates 40 the body of the cart, which is of box form, and is closed at its bottom and sides, and open at its front end. The body is mounted upon wheels 2 carried by an axle 3 which is supported by hangers 4 secured to the 45 side sills 5, the latter being extended rearwardly beyond the body to provide handle bars 6 which are connected by a cross bar 7 in the usual or any ordinary manner, and by which the cart may be pushed or drawn 50 over the ground. The wagon body may be supported in a substantially horizontal position by legs 8, of the usual or any preferred construction. The front end of the body is adapted to be closed by a pair of 55 doors 9 each of which carries a hinge frame 10, and the two horizontal arms 11 of each

frame are provided at their outer end with sockets 12, and in these sockets are secured the terminals of pintles 13. The pintle of each door is supported for rotary movement 60 relative to the body of the cart by a pair of L-shaped brackets 14, suitably secured to the side braces 15, as clearly shown in Fig. 7. Surrounding each pintle is a coiled spring 16, one end of each of which is secured in the adjacent bracket 14, the lower end of the spring being passed through an opening in the pintle adjacent to its lower end. By this it will be seen that the natural 65 tendency of the springs is to force the doors open when they are released, thus to permit the discharge of the contents of the body of the cart. The means for holding the doors normally locked against the outward opening tendency of the springs consists of a 70 latch 17, the shank 18 of which is arranged to slide between guides 19 carried by plates 20 secured to the front cross brace 21 of the body. The shank 18 is a hollow structure 75 and has arranged within it a coiled spring 80 22 the upper end of which engages with a pin 23 depending from the latch, and the lower end of which engages a pin 24 carried by a plate 25 secured to the under side of the cross brace 21, the tendency of the 85 spring being normally to cause the latch to engage with the outer surface of the lower ends of the doors at their meeting points. The means for depressing the shank to move 90 the latch out of locked engagement with the doors consists of a lever embodying three arms 26, 27 and 28, the lever being pivoted at 29 between a pair of keepers 30 depending from the plate 25. The arm 26 engages the lower wall of the slot of the 95 shank, as clearly shown in Fig. 5, beneath the plate 25, and upon the three arm lever being rocked by pressure on the arm 28, which projects in a forward direction, the shank will be drawn downward and thus 100 move the latch out of engagement with the doors whereupon the latter will be released and will be automatically swung into the position shown by dotted lines in Fig. 2. The lever 28 is provided with a foot piece 105 31 by which to facilitate the rocking of the three arm lever, and the arm 27 has connected with it at the point of juncture of the arm 28 one end of a rod 32, the other end of which passes through a keeper 33 secured to 110 the under side of the front cross brace 34, and extends a sufficient distance beyond the

keeper to be within easy reach of the operator when he desires to release the doors from the rear of the machine instead of in front.

5 The form of the invention shown in Fig. 3 is the same as that shown in Fig. 1, except that the back of the body 1 is closed by a head 35.

In the form of the invention shown in 10 Fig. 4, the frame carries a single wheel 36 instead of two wheels, as in the other forms of the invention, this causing the structure, to all intents and purposes, to be a wheelbarrow. A further difference on the construction 15 of the device shown in Fig. 4 over those shown in Figs. 1 and 3 is that the doors 37 close the sides instead of the front end of the body and are released by the same form of locking latch and lever as that shown in the 20 figures first described, and as this will readily be understood, the same reference characters are employed to designate the parts of the locking mechanism.

From the foregoing description it will be 25 seen that while the improvements herein described are simple in character, they will be thoroughly efficient in practice for the purposes designed, and will coact in the production of a barn yard cart that may readily be 30 employed, in any place where an ordinary wheelbarrow can be used, to increased advantage.

Having thus described my invention, what I claim is:

35 1. A vehicle comprising a body, doors for closing a part of the body, spring hinges carried by the doors to normally hold the same in open position, a sliding latch adapted for engagement with the doors at their meeting 40 edges to hold the same closed, and means for releasing the latch from engagement with the doors to permit the doors to automatically open.

2. A vehicle comprising a body, doors for 45 closing a part of the body, spring hinges car-

ried by the doors to normally force the doors to open position, a sliding latch adapted for engagement with the doors at their meeting edges to normally hold the same closed, said latch having a slotted shank projecting 50 therefrom, and an angular lever having one arm engaged with said slotted shank whereby upon movement of the lever the shank may be moved to withdraw the latch from engagement with the doors to permit the 55 doors to be automatically opened.

3. A vehicle comprising a body, doors for closing a part of the body, spring hinges carried by the doors for forcing the doors to open position, a slideable latch adapted for 60 engagement with the doors at their meeting edges to normally hold the same in closed position, a spring for normally holding the latch in engagement with said doors, and means for releasing the latch against the tension of the spring to permit the doors to automatically open.

4. A vehicle comprising a body, doors for closing a part of the body, spring hinges carried by the doors, the tension of the spring 70 hinges normally forcing the doors to open position, a slideable latch having a slotted shank adapted for engagement with the meeting edges of the doors to normally hold the same in closed position, a spring engaged 75 against said latch to normally hold the same against the meeting edges of the doors, an angular lever pivotally connected to the body, one arm of said lever being engaged within the slot in the shank, whereby upon movement of the lever the latch is disengaged from the doors against the tension of said spring, whereby to permit the doors to open automatically.

In testimony whereof I hereunto affix my 85 signature in the presence of two witnesses.

LUCIUS N. WADE.
